COOLING SYSTEM FOR HIGH POWER HIGH FREQUENCY TRANSMITTERS

Louis A. Gebhard, Washington, D. C.

Application December 24, 1930
Serial No. 504,627

7 Claims. (Cl. 250—17)

My invention relates broadly to high frequency transmitters and more particularly to a high power, high frequency electron tube transmitter.

One of the objects of my invention is to provide an arrangement of high frequency electron tube transmitter adapted for high power operation and having a high degree of transmission efficiency.

Another object of my invention is to provide a fluid cooling system for a high power transmitter wherein is a multiplicity of inductance coils connected with the power amplification circuits of the transmitter, the arrangement being such that high frequency losses due to the fluid cooling are substantially eliminated.

Still another object of my invention is to provide an arrangement of fluid cooled inductances in association with a high power electron tube system in a transmitter circuit wherein the cooling fluid is introduced at points in the inductances which are at relatively low potential for eliminating losses of radio frequency energy.

A further object of my invention is to provide an assembly arrangement for a fluid cooled inductance system in a high power high frequency transmitter wherein a single insulating hose coil system may be employed in the fluid cooling circuit to both the high frequency coupling inductance and the high frequency loading inductances of the high frequency oscillation circuits of an electron tube transmitter.

Other and further objects of my invention reside in the method of connecting a multiplicity of inductance coils with a coupling coil in a fluid cooled inductance system for a high frequency transmitter in which high frequency losses may be maintained at a minimum while the uniform temperature may be maintained throughout the inductance system under conditions of high power operation as will be more fully set forth in the specification hereinafter following by reference to the accompanying drawings, wherein:

Figure 1 is an end view showing the arrangement of fluid cooled inductances in association with the fluid cooled coupling coil in the radio frequency amplification circuits of a high power transmitter according to my invention; Fig. 2 is an elevational view of the apparatus illustrated in Fig. 1; Fig. 3 is an enlarged detail view of the fixture for establishing a fluid connection with the central portions of the coupling inductance and the loading coils of the transmitter; Fig. 4 is a theoretical view showing the circulating fluid path through the coupling coil and inductances in the radio frequency system of the transmitter;

and Fig. 5 is a detail view showing the method of interconnecting the low potential points of the loading coils for establishing a fluid cooling path therethrough.

When the power output required from a radio transmitter reaches a certain point it is necessary to employ fluid cooling both for the anodes of the thermionic tubes used as well as the inductance coils in the output circuit and often the input circuits of the high power stages of amplification. When the fluid cooling is used at very high frequencies of operation of the transmitter severe losses are liable to occur at the points where the cooling fluid is admitted to, and discharged from, the high potential circuits unless precautions are taken to locate the points of entrance and discharge of the cooling fluid where the radio frequency potential is a minimum. Such points, however, while at low radio frequency potential are generally at a high direct current potential with respect to ground. It is necessary, therefore, to feed the cooling fluid through an insulating tubing coil and discharge it through a similar coil. This coil is connected between the fluid supply and discharge circuit, which is generally grounded, and the low potential points of the radio frequency circuits. This insulating tubing coil must be of sufficient length to provide a fluid path sufficiently long and of high enough resistance to prevent undue loss of electrical energy.

In the drawings, the fluid cooled tubes are shown at 1 and 1a with their fluid cooling jackets 2 and 2a. The fluid cooling for the thermionic tubes is obtained from source 3. The circulating fluid is passed up through insulating tubing coil 4 to the center of the coil 5. From the center of coil 5 the fluid path divides and passes to jackets 2 and 2a through the coil 5. From the jackets it returns through coil 5 to its center and through the insulating tubing coil 4 out the discharge 6. Coil 5 is arranged to have sufficient inductance to cover the lowest frequency band of the transmitter. Fixed coils 7, 8 and 9 are connected in parallel with coils 5 by means of switching system 10 to provide the proper inductance for the other frequency ranges of the transmitter. Antenna coupling is obtained through coil 11 which is mounted inside of coil 5. Inductance coils 7, 8 and 9 are each self-sustaining and are supported by sets of insulated pins indicated at 20 projecting toward each other from the insulated frame members 21 which are in turn supported upon the frame 22 of the transmitter. The fluid cooled circuits of these

coils are connected in series by means of insulating tubes 12 and 13. The cooling fluid is supplied to the group of coils through insulating tube 14 to the central point on coil 5 to which 5 coil 4 is connected. The discharge is effected in a similar manner through insulating tubing 15 to the fluid circulating coil 4 at a point substantially coinciding with the center of coil 5. The fluid circulating paths in the center of coil 10 5 are shown more clearly in Fig. 3 where 5a and 5b are the tubes which form the conductor of coil 5. Parts 16 and 16a are connected to tubes 5a respectively at the center of coil 5. The ends 15 of these parts 17 and 17a are connected to the coil 4. Electrically conductive tubes 18 and 18a enter into the sides of parts 16 and 16a. The open 20 ends of these tubes are connected to the insulating tubes 18 and 18a, respectively. An electric terminal 8 located between parts 16 and 16a provides a connection to the center of coil 5 for the anode potential.

The electrical and fluid cooled circuits of the complete system are shown more clearly in Fig. 4. In this figure the inductance coils and the 25 insulating tubing coils have been expanded to more clearly illustrate the fluid path. That is to say, the inductances 7, 8 and 9 which consist of tubular members closed at opposite ends with fluid outlet and inlet connections adjacent the 30 center thereof have been drawn in elemental form to show the mechanical equivalent of each of the inductance systems. Each of the inductances 7, 8 and 9 have an interior tube 7a, 8a and 9a disposed therein and supported in the 35 partition members 7b, 8b and 9b in each of the inductances. The remote ends of the tubes constituting inductances 7, 8 and 9 are closed, enabling the fluid to be introduced adjacent the center of the tubes, circulated to one end thereof, returned through the central inner tube to the opposite end thereof and then returned to a point of discharge adjacent the center of the tube.

Fig. 5 shows the method of connecting the fluid 45 cooling circuits of the inductance coils 7, 8 and 9 in series.

It will be seen in Fig. 4 that coils 7, 8 and 9 are successively connected to coil 5. Coil 5 has the anode potential of tubes 1 and 1a connected to it at all times. Any one of the coils 7, 8 and 9 are connected in parallel with coil 5 by means of the switches 10 which may be angularly shifted to engage sets of contacts 7c, 8c or 9c on the inductances 7, 8 and 9, respectively. The switches 50 5 10 are actuated by rotatable shaft member 28 to which crank 29 is connected on the outside of the panel 30 which extends across the front of the radio transmitter. The coupling inductance 11 may be adjusted by means of shaft 31 rotatable from crank 32 on the front of panel 30. A counter 33 is actuated from gear 34 on shaft 31 for resetting the coupling to the desired position for a particular transmission frequency. Coils 7, 8 and 9 have the same direct current potential 55 as coil 5. The center of these coils will have very nearly the same potential as the center of coil 5 as far as radio frequency is concerned and this will be nearly ground potential. Therefore by connecting the fluid cooling circuits to the centers of coils 5, 7, 8 and 9 it is possible to get a very low loss system. In addition to this but one insulating hose coil 4 is necessary. This will supply a fluid inlet and discharge both for the anodes of tubes 1 and 2 for the cooling of coils 70 5, 7, 8 and 9.

In Fig. 4 the tubes have been shown diagrammatically with the anode jackets broken away in order to illustrate the fluid paths through the system. The cathodes have been schematically shown as energized through transformer systems 80 23 and 24, the secondary windings of which are provided with mid-taps 23a and 24a connected to the mid-potential point on coil 5 at binding post 8 through the source of plate potential indicated generally at 25 across which there is provided a by-path condenser 26 in series with inductance 27.

While I have described my invention in certain preferred embodiments I desire that it be understood that modifications may be made and that no limitations upon my invention are intended except those which may be imposed by the scope of the appended claims.

What I claim as new and desire to secure by Letters Patent of the United States is as follows:

1. A tuning system for high frequency transmitters comprising a coupling inductance and a multiplicity of auxiliary inductances, each of said auxiliary inductances being constituted by 100 tubular elements closed at each end thereof and having fluid passages therethrough terminating at the approximate centers thereof and a series arranged fluid connection to the said approximate centers of all of said inductances for effecting a continuous cooling of said coupling and auxiliary inductances independent of the electrical connections thereto.

2. A fluid cooled inductance system for high frequency signaling comprising in combination 110 a coupling inductance and a multiplicity of auxiliary inductances, said coupling inductance comprising a dual fluid passage, said auxiliary inductances each having the ends thereof closed, fluid inlet and discharge connections between 115 the approximate centers of said auxiliary inductances and the central portion of the dual fluid passage of said coupling inductance and a cooling coil disposed in series with said inlet and discharge connections for supplying cooling fluid through all of said inductances in a series path at points of minimum potential of said inductances.

3. A tuning system for high frequency transmitters comprising a coupling inductance constituted by a dual tubular conductor, a multiplicity of auxiliary inductances, a dual passage cooling coil, and fluid connections between the dual passage cooling coil and the approximate 125 centers of said auxiliary inductances and the central portion of said dual conductor in series for circulating cooling fluid through said inductances and maintaining all of said inductances at uniform temperature independent of the electrical connection thereto.

4. A high frequency signaling system comprising a push-pull amplifier circuit, a coupling inductance constituted by a dual tubular conductor connected at the opposite ends thereof with parts of said push-pull amplifier circuit, a multiplicity of auxiliary inductances each consisting of a tubular conductive member closed at opposite ends thereof and having fluid passages intermediate said ends, and a fluid circulating 140 tube connecting the approximate centers of said auxiliary inductances with the central turns of the dual conductor constituting said coupling inductance for supplying cooling fluid to said several inductances in series at points of minimum 145 150

potential thereof and a cooling coil in series with said fluid circulating tube.

5. In a high frequency signaling system, a push-pull amplifier circuit, a coupling inductance constituted by a twin tubular conductor having the ends thereof connected to portions of said push-pull amplifier circuit, a multiplicity of auxiliary inductances each consisting of a tubular conductor closed at each end thereof, fluid connections between the approximate centers of said auxiliary inductances with the central portion of said coupling inductances for maintaining all of said inductances at uniform temperature independent of electrical connections to said inductances, a dual passage cooling coil connected in series with said fluid connections and means for establishing electrical connection with a selected auxiliary inductance independent of the paths for circulating cooling fluid therethrough.
- 10 6. In a high frequency tuning system for signaling circuits, a coupling inductance constituted by a tubular conductor, a push-pull amplifier circuit including a pair of electron tubes having fluid cooled elements, fluid connections between the ends of the twin tubular conductor constituting said coupling inductance and the fluid cooled elements of the electron tubes, a plurality of auxiliary inductances each having different

frequency characteristics and each consisting of tubular conductors closed at opposite ends thereof, and a series connected dual passage cooling coil disposed in the fluid cooling path extending from the central portion of said coupling inductance through the centers of each of said auxiliary inductances for maintaining said coupling inductance and said auxiliary inductances at uniform temperature.

- 80 7. A high frequency inductance system comprising a main inductance and a plurality of auxiliary inductances of differing frequency characteristics, a cooling coil, said main inductance being constituted by a twin tubular conductor having fluid inlet and outlet connections adjacent the centers thereof, said auxiliary inductances being constituted by concentric tubular members with fluid inlet and outlet connections and insulated tubular members connecting said cooling coil with the inlet and outlet connections to said main inductance and the fluid inlet and outlet connections of said auxiliary inductances at the approximate centers thereof independent of electrical connections to said inductances for establishing a series circulating path for cooling fluid through all of said inductances.
